M. WALD

COLLAR

Filed March 2, 1923

UNITED STATES PATENT OFFICE.

MAX WALD, OF NEW YORK, N. Y.

COLLAR.

Application filed March 2, 1923. Serial No. 622,367.

To all whom it may concern:

Be it known that I, MAX WALD, a citizen of the United States, and a resident of the city of New York, borough of Manhattan, 5 in the county of New York and State of New York, have invented a new and Improved Collar, of which the following is full, clear, and exact description.

This invention relates to improvements 10 in wearing apparel, and has particular reference to a collar.

It is well known that turn-down collars, and particularly those which are starched when laundered, very often tear around the 15 button-holes and at the ends of the folding line which forms the junction between the neckband and flap portions so that the collar is, in a comparatively short time, rendered useless.

20 An object of the present invention is to overcome the above difficulty by providing a collar embodying an improved construction, wherein the sections or plies thereof are so made and assembled to form the completed article that the possibility of the 25 material tearing about the button-holes or at the ends of the folding line is reduced to a minimum.

Another object is to improve the construction of the collar by providing a plurality of sections each of which is utilized 30 to form parts of both the band and flap portions and which have secured thereto a reinforcing strip, one edge of which defines the 35 folding line of the collar.

The above and other objects will appear 40 more clearly from the following detail description, when taken in connection with the accompanying drawing, which illustrates preferred embodiments of the inventive idea.

In the drawing—

Figure 1 is a plan view of the completed collar, partly broken away to illustrate the interior construction;

45 Figure 2 is a section on the line 2—2 of Figure 1;

Figure 3 is a transverse sectional view 50 through the collar illustrating the manner in which certain parts of the collar are assembled;

Figure 4 is a section on the line 4—4 of Figure 1;

Figure 5 is a plan view of one of the end reinforcing strips employed in connection with the invention; and

55 Figure 6 is a view similar to Figure 3 showing a different form of the invention.

Referring more particularly to Figures 1 to 5 inclusive, the collar illustrated in these figures is of the turn-down type and may be 60 either a soft or stiff collar. Broadly, the collar is shown as including the neckband and flap portions 7 and 8, respectively. In making the collar the portions 7 and 8 are formed by employing two complementary 65 sections or plies 9 and 10, the width of each of which is substantially equal to the combined widths of the portions 7 and 8. By forming the sections in this manner, the usual method of making a collar in which 70 the sections or plies are stitched together to provide a folding line is obviated. The sections 9 and 10 are first secured together along adjacent longitudinal edges by a row 75 of stitches 11, after which a reinforcing strip or counter 12 of substantially the length of said sections is secured to the section 9 by a row of stitches 13, said reinforcing strip being preferably folded upon itself, as shown in Figure 3, to increase the 80 thickness thereof. This strip 12 is secured in position intermediate the longitudinal edges of the section 9 and the upper longitudinal edge of said strip is utilized to define the folding line of the collar, as illustrated in Figure 2, which forms the juncture 85 between the portions 7 and 8. When stitching the strip 12 in position the end reinforcing strips 14 are also placed in position at the ends of the strip 12, said strips 14 90 being of a size to overlap parts of the band and flap portions of the collar and the outer edges of said strips 14 are cut to conform to the contour of the ends of said portions 7 and 8. Parts of the strips 14 also surround 95 the end button-holes 15 in the collar so as to reinforce these holes when the same are formed. An intermediate reinforcing strip 16 is also secured in position when the strip 12 is being stitched to the section 9 and this 100 intermediate strip 16 also has a portion surrounding the rear button-hole 17 formed in the band portion of the collar so as to reinforce said hole.

After the strips 12, 14 and 16 have been secured in position, the sections 9 and 10 are reversed, as indicated in dotted lines in Figure 3, so that said strips will be interposed between the sections and thus be invisible when the collar is in its completed state. Following the reversing operation the sections are sewed together about their edges by a second row of stitches 18, which not only secure the sections together, but extend through the strips 14 and 16 adjacent their outer edges so that said strips will be securely maintained in proper position.

In the form of the invention shown in Figure 6, the reinforcing strip 12' which is secured to the section 9' is shown as consisting of four thicknesses instead of two and instead of only utilizing one other section in connection with the section 9 two sections

10' may be employed, thus imparting to the collar an added thickness which will give it more rigidity when being worn.

What is claimed is:

A turn-down collar, comprising two similarly shaped sections secured together to 25 overlie one another, each section consisting of a neck band portion and a flap portion integral with the neck band portion, and a strip folded upon itself and secured at its folded edge only to the inner face of one 30 of the sections at the junction of its neck band and flap portions, whereby a comparatively narrow and thick strip is provided which lies between the said sections so as to be entirely concealed and which clearly 35 defines the folding line between the neck band and flap portions of the collar.

MAX WALD.
